UNITED STATES PATENT OFFICE

2,346,158

DRIVING MECHANISM

John B. Dyer, Syracuse, N. Y., assignor to General Motors Corporation, Dayton, Ohio, a corporation of Delaware

Original application June 29, 1940, Serial No. 343,206. Divided and this application June 16, 1943, Serial No. 491,032

17 Claims.

(Cl. 74—23)

This invention relates to driving mechanisms and the like.

An object of this invention is to provide a transmission for rotating a basket or the like and vertically reciprocating an agitator or the like.

This application is a division of my copending application Serial No. 343,206, filed June 29, 1940, for Domestic appliance.

Further objects and advantages of the present invention will be apparent from the following description, reference being had to the accompanying drawings, wherein a preferred form of the present invention is clearly shown.

In the drawings:

Fig. 1 is a view, partly in section and partly in elevation of a washing machine embodying my invention, the view being partly diagrammatic;

Fig. 2 is a vertical cross-section of the transmission mechanism for imparting rotation to the tub and reciprocation to the agitator;

Fig. 3 is a horizontal cross-section taken along the lines 3—3 of Fig. 2.

Fig. 4 is a horizontal cross-section taken along the lines 4—4 of Fig. 2.

Fig. 5 is an enlarged cross-sectional view of the upper part of the machine; and

Fig. 6 is a cross-sectional view taken along the line 4—4 of Fig. 2.

The driving mechanism, which is claimed in this application, may be used to drive any suitable device. For example, it may drive a washing machine having a rotatable tub 10 and an agitator 11 therein. An automatic counterbalancing device 12 may be attached to the machine below the tub 10, which forms no part of the present invention, and includes a mass of counterbalancing liquid, such as water, mercury, or heavy oil or its derivatives, which is automatically distributed in the machine during the pick-up of rotation so that the same automatically balances the unbalance created by any unequal distribution of clothes within the tub.

The counterbalancing device 12 includes a receptacle 13 and liquid pocket means 14 located above the receptacle 13. The receptacle 13 and pocket means 14 are connected by proper liquid passageways 15 in such a manner that the passageways 15 receive liquid from the receptacle 13 and distribute it to the pocket means 14 in such quantities that any unbalance in the machine tends to be correctly counterbalanced by the liquid, as more fully described and claimed in my said copending application.

The tub 10, and its driving mechanism 16 preferably are mounted on a universal joint 17 to allow a slight movement about the joint 17 as a fulcrum. The mechanism is maintained in a vertical position by the resilient rubber-like supports 18.

Air relief pipes 13a are provided to prevent trapping of air in the pocket means 14. These pipes 13a extend from the floor of the pocket means 14a to a point 13b near the inner wall of the receptacle 13 and above the normal liquid level in receptacle 13. The position of these pipes is such that air relief is afforded the pocket means 14; but liquid does not flow upwardly through them, because the terminal 13b is so located that such flow is prevented.

A trough 40 is placed around the centrifugal basket 10 and is adapted to receive liquid discharged over the flange 41 of the basket.

The particular construction of the tub 10, is of no particular importance, preferably is as indicated in Figs. 1 and 5. Thus the tub may include an outer cylindrical imperforate portion 45 within which is nested an annular shell 46. The annular shell 46 is provided with a lower flange 47 provided with openings 48 and is also provided with openings 49 approximately along the middle. The total discharge capacity of the openings 48 preferably is more than that of the openings 49. The object of this construction is to remove the scum from the washing liquid before the same has been deposited on the clothes 19, 20 during the centrifugal action. The scum is removed automatically because, as the tub begins to rotate, the liquid takes the form of a vortex, with a large amount of liquid being discharged through the openings 48 and flowing up through the passage 50 over the rim 41. The scum tends to flow along the surface of this vortex down near the openings 43 where the scum is removed along with the liquid flowing through the openings 49.

The agitator 11 preferably is of the vertically reciprocated type, and includes the metal cone-shaped portion 11a and the resilient, rubber-like flange 11b along the lower periphery. This agitator is reciprocated with short strokes of about one and one-half inches in length at about 450 R. P. M. to produce a toroidal action in the clothes and washing liquid while the tube 10 is stationary. This tends to distribute the clothes within the tub 10 somewhat evenly in a ring about the agitator 11. However, this distribution obviously is not always exactly even, and

larger masses of clothes may be gathered along one side of the machine, as indicated at 19. After agitation has been completed, the agitator preferably is stopped, and the tub is rotated (along with the agitator 11), to discharge the liquid and scum through the openings 48 and 49. During the pick-up of this rotation, the liquid in receptacle 13 is automatically distributed to the pockets 14, 14a as previously described, in a manner to effect a substantial counterbalance of the unequally distributed clothes 19, 20.

The driving mechanism for actuating the agitator and rotating the tub, which is the subject of the present invention, is disclosed in Figs. 2, 3, 4, 5 and 6, which is constructed as follows:

A transmission casing 50a, 51 is provided and is bolted together as shown. This casing contains a motor having rotor 52 and a stator 53. This motor is reversible. When rotated in one direction, it causes the agitator shaft 54 to reciprocate vertically. When the motor rotates in the other direction, it rotates the tub 10, along with the agitator 11.

The agitator shaft 54 is vertically reciprocated by causing the motor to rotate the cage 55. This cage carries pulleys 56 which straddle a non-rotatable undulating track 57, which is fixed to the shaft 54. As the pulleys 56 rotate, they cause the track 57 to reciprocate vertically, and impart a reciprocating motion to the shaft 54 to which it is attached by means of the bolt 57a passing through the bearing 57b.

The cage 55 is rotated by means of planetary gears. The motor shaft 58 is fixed to the sun gear 59. The sun gear 59 drives a ring 60 carrying planetary gears 61, which are meshed to the outer gear ring 62 carried by the cage 55. The planet ring 60 extends vertically inside a set of unidirectional clutches 63, such that, when the planet ring is urged in one direction, its rotation is stopped by the clutches 63; but is allowed to rotate when it is urged in the other direction. As a result, when the motor shaft 58 rotates in one direction, the planet ring 60 is held stationary with the result that the gear 59 drives the gear 62 through the planet gears 61, thus rotating the cage 55 at a less number of cycles per unit of time than the motor speed and causing vertical reciprocation of the agitator 11 also at a less number of cycles per unit of time than the motor speed.

For the purpose of facilitating construction, the planet ring 60 rides about a bearing ring 64. The sun gear 59 is pressed on the shaft 58 and is secured thereto by the nut 65. The shaft 58 rides in bearing 66 carried by the casing 50a. The unidirectional clutches 63 are carried by a stationary ring 67 secured to the casing 50a.

Rotation of the tub 10 is accomplished by rotation of the motor in the opposite direction. Such rotation causes the clutch plate 70 to rise into engagement with the clutch face 71 and causes the combined clutch and brake plate 72 to be lifted. This disengages the brake band 73 from the stationary brake plate 74 and allows the plate 72 to rotate along with the rotating clutch plate 70. The plate 72 is keyed to the shaft 75, which in turn is keyed at 75a to the tub carrying shaft 76. The shaft 76 has a tub carrying plate 76a to which the tub is bolted by bolts 10b along with the plate 36 and spacer ring 36a. The shaft 76 is carried by thrust ball bearings 76b.

The rotating plate 70 is lifted into engagement with the clutch band 71 by means of the

spiral drive 77. The motor shaft 58 is provided with spiral slots 77 in which screws 78 extend. The screws 78 are carried by the vertical sleeve 79 which carries the clutch plate 70. As a result of this, when the motor shaft 58 is rotated in the proper direction, the plate 70 is lifted by the well-known spiral action into engagement with the clutch band 71 to rotate the tub 10 at the same speed as said motor. The plate 72 is urged downwardly by the spring 81 to insure a driving engagement between the plate 70 and band 71 and also to bring the brake band 73 into engagement with the plate 74 when the motor is stopped or reversed. The agitator shaft 54 is held in alignment at the upper end by bearing 54a. A flexible bellows 54b, made of rubber or metal is secured to the shaft 54 and to the cone washer 10a which is held by the bolts 10b.

Proper lubrication is provided. To this end the casing 51 is provided with a lubricant cup 85, and lubricant is poured to the proper level. It flows through passages 86 into the space 87, from whence it is pumped through the valve 88 into the interior of the shaft 54 by the reciprocating action of shaft 54. This oil is pumped up to the oil hole 89 to provide proper lubrication between the shaft 54 and the shaft 75. The oil flows down between these two shafts and may pass out through the oil hole 90 for further lubrication of the parts and 30 may be discharged through the opening 92. Other portions of the oil stream may flow down to the opening 93 and lubricate the parts at this portion of the mechanism.

The shaft 54, and track 57, are held non-rotationally, when the tub is stationary, by the brake 73, since brake plate 72 is keyed to shaft 75, which in turn is keyed to bearing 57b which is bolted to shaft 54. Thus when the brake is applied to the tub, the shaft 54 and track 57 are held non-rotationally, to enable them to be vertically reciprocated by the wheels 56 when agitation is required.

The driving clutch 70, 71 can slip during the start of rotation, and this prevents an overload of the motor and further increases the length of rotation at slow speed.

When the tub starts to rotate, the washing liquid gradually rises along the outer side of the tub until it reaches the flange 41. At this time there is a pumping action from the liquid inside of tub 46 to the flange 41. This pumping action has an increasing head to combat as the level of the washing liquid falls inside the tub 46. This pumping action also requires a substantial amount of power and this prevents the motor from accelerating the rotation of the tub for a considerable length of time. During this time, the counterbalancing liquid is properly distributed from the receptacle 13 to the pocket means 14.

The extra load imposed on the motor to accelerate the tub and also to pump the liquid out of the tub, is compensated by the construction of the clutch 70 and 71 which allows it to slip during this starting period and thus relieves the motor from too heavy a burden and at the same time further extends the period of rotation below the "critical speed". This further insures proper distribution of the balancing liquid from receptacle 13 to pocket means 14.

From the foregoing it is evident that the ordinary characteristic of a centrifugal basket to sway with the unbalanced load below "critical speed" cooperates with the delaying washing liquid pumping action and with the delaying slip-

ping action of the clutch 70, 71 to insure proper distribution of the balancing liquid.

While the form of embodiment of the invention as herein disclosed, constitutes a preferred form, it is to be understood that other forms might be adopted as may come within the scope of the claims which follow.

What is claimed is as follows:

1. A driving mechanism comprising a reversible motor, a rotatable shaft, a reciprocable shaft, means for drivingly connecting said motor to said rotatable shaft when said motor rotates in one direction to rotate said rotatable shaft while preventing reciprocation of said reciprocable shaft, and means for drivingly connecting said motor to said reciprocable shaft when said motor rotates in the opposite direction to reciprocate said reciprocable shaft while preventing rotation of said rotatable shaft. 10
2. A driving mechanism comprising a sleeve member and a shaft member coaxially arranged, one of said members being a rotatable member and the other being a reciprocable member, a reversible motor, means for drivingly connecting said motor to rotate one of said members when said motor rotates in one direction while preventing reciprocation of said reciprocable member, and means drivingly connecting said motor to reciprocate the other of said members when said motor rotates in the other direction while preventing rotation of said rotatable member. 20
3. A driving mechanism comprising a rotatable sleeve and a reciprocable shaft coaxially arranged, electrically controlled transmission means for rotatably driving said sleeve and reciprocable shaft together while preventing reciprocation of said reciprocable shaft, and electrically controlled transmission means for reciprocating said shaft while preventing rotation of said rotatable sleeve. 30
4. A driving mechanism comprising a sleeve member and a shaft member coaxially arranged, one of said members being a rotatable member and the other being a reciprocable member, electrically controlled transmission means for rotatably driving said rotatable member while preventing reciprocation of said reciprocable member, and electrically controlled transmission means for reciprocably driving said reciprocable member while preventing rotation of said rotatable member. 40
5. A driving mechanism comprising a transmission housing, a rotatable driven shaft extending from said housing, a reciprocable driven shaft coaxial with said rotatable shaft and extending from said housing, power means within said housing, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft. 50
6. A driving mechanism comprising a reversible motor, a rotatable shaft, a reciprocable shaft, means for drivingly connecting said motor to said rotatable shaft when said motor rotates in one direction to rotate said rotatable shaft while preventing reciprocation of said reciprocable shaft and including a one-way clutch, and means for drivingly connecting said motor to said reciprocable shaft when said motor rotates in the opposite direction to reciprocate said reciprocable shaft while preventing rotation of said rotatable shaft. 60
7. A driving mechanism comprising a revers- 70
- ible motor, a rotatable shaft, a reciprocable shaft, means for drivingly connecting said motor to said rotatable shaft when said motor rotates in one direction to rotate said rotatable shaft while preventing reciprocation of said reciprocable shaft, and means for drivingly connecting said motor to said reciprocable shaft when said motor rotates in the opposite direction to reciprocate said reciprocable shaft while preventing rotation of said rotatable shaft and including rotary-reciprocating mechanism for said reciprocable shaft and brake means for said rotatable shaft automatically rendered effective when said motor rotates in the last named direction. 15
8. A driving mechanism comprising a sleeve member and a shaft member coaxially arranged, one of said members being a rotatable member and the other being a reciprocable member, electrically controlled transmission means for rotatably driving said rotatable member while preventing reciprocation of said reciprocable member, and electrically controlled transmission means for reciprocably driving said reciprocable member while preventing rotation of said rotatable member and including a rotatable cage having rotary-reciprocating transforming mechanism connected to said reciprocable member, clutch means connected to said rotatable member, and brake means connected to said rotatable member. 25
9. A driving mechanism comprising a sleeve member and a shaft member coaxially arranged, one of said members being a rotatable member and the other being a reciprocable member, electrically controlled transmission means for rotatably driving said rotatable member while preventing reciprocation of said reciprocable member and including clutch means for said rotatable member rendered effective and brake means for said rotatable member rendered ineffective during the rotation of said rotatable member, and electrically controlled transmission means for reciprocably driving said reciprocable member while preventing rotation of said rotatable member and including rotary-reciprocation transforming mechanism connected with said reciprocable member rendered effective while said brake means is also rendered effective during reciprocation of said reciprocable member. 35
10. A driving mechanism comprising a transmission housing, a rotatable driven shaft extending from said housing; a reciprocable driven shaft coaxial with said rotatable shaft and extending from said housing, power means within said housing, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft and including a combined brake and clutch plate rendered effective to clutch and ineffective to brake said rotatable driven shaft during rotation thereof and rendered ineffective to clutch and effective to brake said rotatable driven shaft during reciprocation of said reciprocable driven shaft. 45
11. A driving mechanism comprising a transmission housing, a rotatable driven shaft extending from said housing, a reciprocable driven shaft coaxial with said rotatable shaft and extending from said housing, power means within said housing, and electrically controlled transmission means within said housing between said

power means and driven shafts selectively to rotate said rotatable driven shaft while preventing reciprocation of said reciprocable driven shaft and to reciprocate said reciprocable driven shaft while preventing rotation of said rotatable driven shaft and including a rotatable cage carrying rotary-reciprocating transforming mechanism connected to said reciprocable driven shaft.

12. A driving mechanism comprising a transmission housing, a rotatable driven shaft extending from said housing, a reciprocable driven shaft coaxial with said rotatable shaft and extending from said housing, power means within said housing including a motor having a drive shaft coaxial with said driven shafts, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft.

13. A driving mechanism comprising a transmission housing, a rotatable driven shaft extending from said housing, a reciprocable driven shaft coaxial with said rotatable shaft and extending from said housing, power means within said housing including a motor having a drive shaft coaxial with said driven shafts, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft and including a rotatable cage coaxial with said motor and carrying rotary-reciprocating transforming mechanism connected to said reciprocable driven shaft.

14. A driving mechanism comprising a transmission housing, a rotatable driven shaft extending from said housing, a reciprocable driven shaft coaxial with said rotatable shaft and extending from said housing, power means within said housing including a reversible motor, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft and including a combined brake and clutch plate rendered effective to clutch and ineffective to brake said rotatable driven shaft during rotation of said motor in one direction and rendered ineffective to clutch and effective to brake said rotatable

driven shaft during rotation of said motor in the opposite direction.

15. A driving mechanism comprising a transmission housing, a rotatable driven shaft extending from said housing, a reciprocable driven shaft coaxial with said rotatable shaft and extending from said housing, power means within said housing including a reversible motor, and electrically controlled transmission means within said housing between said power means and driven shafts selectively to rotate said rotatable driven shaft while preventing reciprocation of said reciprocable driven shaft and to reciprocate said reciprocable driven shaft while preventing rotation of said rotatable driven shaft and including a combined brake and clutch plate rendered effective to clutch and ineffective to brake said rotatable driven shaft during rotation of said motor in one direction and rendered ineffective to clutch and effective to brake said rotatable driven shaft during rotation of said motor in the opposite direction, and a rotatable cage carrying rotary-reciprocating transforming mechanism connected to said reciprocable driven shaft, said cage being rotated by a one-way clutch when said motor rotates in one direction and being held stationary when said motor rotates in the other direction.

16. A driving mechanism comprising a sleeve member and a shaft member coaxially arranged, one of said members being a rotatable member and the other being a reciprocable member, a motor, electrically controlled transmission means for rotatably driving said rotatable member from said motor at the same speed as said motor while preventing reciprocation of said reciprocable member, and electrically controlled transmission means for reciprocably driving said reciprocable member from said motor at a different number of cycles per unit of time than the speed of said motor while preventing rotation of said rotatable member.

17. A driving mechanism comprising a sleeve member and a shaft member coaxially arranged, one of said members being a rotatable member and the other being a reciprocable member, a motor, electrically controlled transmission means for rotatably driving said rotatable member from said motor at one ratio to motor speed while preventing reciprocation of said reciprocable member, and electrically controlled transmission means for reciprocably driving said reciprocable member from said motor at a different ratio to motor speed while preventing rotation of said rotatable member.
